[57] ABSTRACT

Curl corrector apparatus for operating on a continuous travelling web of paper, cardboard or like material, is arranged between two pairs of web guide rollers. Two similar curl corrector rods are rotatably mounted parallel to each other and to the web guide rollers between the latter. Means are provided for shifting these corrector rods to opposite sides of the straight line path between the guide rollers so that one or the other operates to correct curl. Support rollers back-up these corrector rods, which may also be urged together to provide a nip for the web. The corrector rods are guided by pivoting links or rails.

FIG. 5.

CURL CORRECTOR APPARATUS FOR OPERATING ON A CONTINUOUS WEB

This invention relates to curl corrector apparatus for operating on continuous travelling webs of paper, cardboard or like material. When such material is unwound from a reel, it has an inherent tendency to curl in the same direction as it has been previously wound, and this tendency becomes particularly apparent when the material is cut into individual sheets. Previously proposed curl corrector apparatus comprises a rotatable bar of comparatively small diameter over which the web is deflected in the opposite sense to its tendency to curl. The curl corrector rod is normally provided with support rolls on its side remote from the web to reduce bending of the rod.

The sense in which the reel is unwound and consequently the direction of curl of the web may be in either direction according to the number of previous occasions on which the web has been reeled during preliminary processing. The known curl corrector apparatus can, however, only deal with curl in one direction and so it is necessary for a reel with the opposite direction of curl to be rewound before that curl corrector apparatus can be used.

According to the present invention a curl corrector apparatus for operating on a continuous travelling web of paper, cardboard or like material, comprises two similar curl corrector rods mounted on opposite sides of the path of the web between two pairs of web guide rollers and displaceable transversely to the path of the web, so that the curl corrector rods are respectively capable of deflecting the web to opposite sides of the straight line path between the pairs of guide rollers, for correction of curl in either direction.

The two curl corrector rods may be rotatably carried by a common mounting element at each end displaceable transversely to the path of the web. The common mounting elements may also carry two pairs of support rolls, each pair being arranged side by side and contacting the curl corrector rod on its side away from the web.

Preferably the mounting elements are guided in their transverse displacement so that the angle formed by the deflected path of the web is always substantially bisected by the plane which passes through the axis of the curl corrector rod which is deflecting the web and passes equidistantly between its support rolls.

For example the mounting elements may be guided by means of a pivotal linkage comprising, for each mounting element, a pair of non-parallel swinging arms pivoted at one of their ends at spaced positions on a fixed part of the apparatus adjacent to one of the pairs of guide rollers, and pivoted at their other ends at spaced positions on the respective mounting element. Alternatively the two mounting elements may each be formed by a pivotal arm which is pivoted at one end to a fixed part of the apparatus adjacent to one of the pairs of guide rollers and carries one end of each of the two curl corrector rods at its other end, the support rolls being carried by the pivotal arms through links which are pivoted to the arms on the axes of the respective curl corrector rods and which are connected by further links to spaced pivots on the fixed part. In a further alternative, the mounting elements may be guided on rails extending transversely to the straight line path between the pairs of guide rollers.

Means may be provided for urging the two curl corrector rods against one another, so that the one which is not acting as a curl corrector at any given time will serve as an additional support roll for the one which is so acting.

The invention may be performed in various ways and some specific embodiments thereof will now be described, by way of example, with reference to the accompanying drawings, in which:

10 FIG. 1 is a diagrammatic vertical section through a curl corrector apparatus,

FIG. 2 is a similar section through a second form of apparatus,

FIG. 3 is a similar view of a third embodiment,

FIG. 4 is a similar view of a fourth embodiment,

FIG. 5 is a partial underneath plan view of the embodiment of FIG. 4, and

FIG. 6 is a diagrammatic vertical section through a further embodiment.

20 In the apparatus shown in FIG. 1, the web W is drawn from a reel (not shown) to the left hand side of the figure, passes between a pair of guide rolls 10,11 mounted in a fixed part 12 of the apparatus and is drawn off between a further pair of guide rolls 13,14 mounted on the fixed part 12. From there the web is directed to a transverse cutting apparatus (not shown).

A pair of rotatable circular-section curl corrector rods 16,17 are mounted at their respective ends in a pair of vertical plate-like mounting elements 18, of which only one is visible in FIG. 1. It is shown in one curl-correcting position in full lines and in alternative positions in broken lines. Each curl corrector rod 16,17 is supported by a respective pair of backing or support rolls 19,20, mounted so as to contact the respective curl corrector rod on its side remote from the web W. Each pair of support rolls 19,20 is formed by a series of pairs of short aligned rolls in known manner, each individual pair of rolls being mounted in a respective bracket 191,201. The brackets 191,201 are mounted on transverse beams 192,202 secured at their ends to the plate-like mounting elements 18.

The curl corrector rods 16,17 are not positively located in the mounting elements 18 but have limited freedom to float laterally. Spherical ball bearing supports (not shown) at each end confine the rods axially. Each of the rods 16,17 is prevented from falling out of place by the other rod and by its support rolls.

Each of the plate-like elements 18 is supported at 25,26 at the ends of a pair of non-parallel pivoted arms 21,22 whose other ends are pivoted at 23,24 respectively on the fixed part 12 of the apparatus. The spacing between the pivots 25,26 of the arms 21,22 on the plates 18 is greater than the spacing between their pivots 23,24 on the part 12, so that the plane 27 which passes through the axes of the curl corrector rods 16,17 and is equidistant from the rollers of the respective pairs 19,20 always bisects the angle made by the web W as it is deflected by either of the curl corrector rods 16,17. A leadscrew actuator 15 having a protective bellows 151 is connected to each of the plate-like elements 18 for displacing them transversely to the web W.

It will be realised that, by thus displacing the plate-like mounting elements 18 transversely to the web W on the pivotal arms 21,22 the web W can be deflected either upwardly or downwardly so as to correct curl in either direction.

The embodiment of FIG. 2 is generally similar to that of FIG. 1 except that the two curl corrector rods 16,17 are mounted at each end in one of a pair of common pivoted arms 30, only one of which is visible. The arms 30 are pivoted on a horizontal axis 37 on the fixed part 12, midway between the axis 35,36 of the guide rollers 13,14. The support rolls 19,20 are carried by the arms 30 through links 31,32 which are pivoted on the arms 30 coaxially with the curl corrector rods 16,17. The ends of the links 31,32 remote from the arms 30 are pivotally connected at 37,38 to further links 33,34 pivoted on the fixed part 12 on the axes 35,36 of the guide rollers 13,14.

The distance between the pivot axes of each link 31,32 (i.e. the distance between the axis of the rod 16 and pivot 37 and the distance between the axis of rod 17 and pivot 38) is greater than the distance between the axis 35,36 of the respective link 33,34 and the pivot axis 37 of the arm 30, so that as in the previous embodiment the angle formed by the deflected web W will always be bisected by the plane which passes through the curl corrector rod 16 or 17 currently in use and which also passes equidistantly between the support rolls of that rod.

In the embodiment of FIG. 3, the lower curl corrector rod 16 and its support rolls 19 are mounted at their respective ends in plate-like mounting elements 181 which are mounted on pivoted arms 21,22 as in the embodiment of FIG. 1. The upper curl corrector rod 17 and its support rolls 20 are mounted at their ends in plates 182 slidable in the mounting elements 181 parallel to the length of the latter, i.e. transversely to the web W.

Upper and lower jaws 41,42, having a common pivot 43 on the plate-like element 181, are connected respectively to the slidable plate 182 and to the mounting element 181. The jaws 41,42 can be opened and closed by a diaphragm actuator 44. They are opened for insertion of the web W and may be subsequently closed so that the rods 16,17 are urged against one another and the one which is at any time not acting as a curl corrector will serve as a further support roller for the one that is so acting. Similar means may be provided in the embodiments of FIGS. 1 and 2 for urging the curl corrector rods 16,17 against one another for the same purpose.

In the embodiment of FIGS. 4 and 5, the curl corrector rods 16,17 are mounted in plate-like mounting elements 183 which are formed in two parts 184,185, hinged together at 45. Relative pivotal movement of the two parts 184,185 is effected by a diaphragm actuator 46. Opening movement, for introduction of the web W, is limited by an end stop 47. When the parts 184,185 are closed together, the gap between the rods 16,17 may be greater than the thickness of the web W, or the rods may be urged together so that the one supports the other.

Although it is preferred to carry the mounting elements 18,181,183 on pivotal arms 21,22 they can be guided on rectilinear rails extending at right angles to

the straight line path of the web between the pairs of guide rollers. This is shown diagrammatically in FIG. 6 where the corrector rods 16,17 are mounted in a carriage 51 which spans rails 52 each side of the web path and perpendicular thereto mid-way between the guide roll pairs 10,11 and 13,14. The end plates 186 of the carriage form the mounting elements and have wheels or sliding shoes 53 that co-operate with the rails 51.

We claim:

1. A curl corrector apparatus for operating on a continuous travelling web of paper, cardboard or like material between two pairs of web guide rollers, comprising two similar curl corrector rods, mounting means for said rods for maintaining them on opposite sides of the path of the web between said pairs of web guide rollers, two pairs of support rolls carried by the mounting means, each pair being arranged side by side and contacting an associated curl corrector rod on its side away from the web, means for displacing said mounting means transversely to the path of the web between opposite sides of the straight line path between the pairs of guide rollers for correction of curl in either direction, and guide means for the mounting means to maintain the latter in their transverse displacement so that the angle formed by the deflected path of the web is always substantially bisected by the plane which passes through the axis of the curl corrector rod which is deflecting the web and equidistantly between its support rolls.
2. An apparatus according to claim 1, wherein the mounting means include a common mounting element at each end of the curl corrector rods and by which said rods are rotatably carried.
3. An apparatus according to claim 2, wherein said guide means includes a pivotal linkage comprising, for each mounting element, a pair of non-parallel swinging arms pivoted at one of their ends at spaced positions on a fixed part of the apparatus adjacent to any of the pairs of guide rollers, and pivoted at their other ends at spaced positions on the respective mounting element.
4. An apparatus according to claim 2, wherein said guide means includes pivotal arms each pivoted at one end to a fixed part of the apparatus adjacent to one of the pairs of guide rollers, the other ends forming said mounting elements, and carrying one end of each of the two curl corrector rods, links pivoted to the arms on the axes of the respective curl corrector rods and carrying said support rolls, and further links connecting the first mentioned links to spaced pivots on the fixed part.
5. An apparatus according to claim 2, wherein said guide means includes rails extending transversely to the straight line path between the pairs of guide rollers and on which the mounting elements are carried.
6. An apparatus according to claim 1, wherein means are provided for urging the two curl corrector rods against one another, so that the one which is not acting as a curl corrector at any given time will serve as an additional support roll for the one which is so acting.
